UNDERCUTTING AND CONVEYING ELEMENT

Charles E. Tibbals, Bluefield, W. Va.

Application June 14, 1945, Serial No. 599,471

8 Claims. (Cl. 262—8)

This invention relates to an improved undercutting and conveying element, for coal mining machines, of that type embodying a substantially horizontal plate which is reciprocated so as to have a quick movement in one direction and a slow movement in the other direction, and which has cutting bits along one edge arranged to undercut the coal during the slow movement of the element, the coal being delivered by the element to a receiving conveyor during the slow movement thereof.

Coal veins are often irregular, so that the floor of the mine is found to slope upwardly and then downwardly as the mining proceeds. So far as I am aware, these undercutting and conveying elements have been more or less rigid substantially throughout, and it has been difficult, if not impossible, to cause the bits thereof to follow the irregularities of the mine floor.

The primary object of the present invention, therefore, is to provide an undercutting and conveying element including a plate having an edge portion to which the bits are attached, which edge portion is freely flexible vertically, and wherein means is provided to flex such edge portion at will and to the desired degree so as to cause the bits to properly follow the irregularities of the mine floor.

A further object of the invention is to provide an element of the above kind in which fluid pressure is utilized to flex the edge of the element.

Another object of the invention is to provide an element of the above kind which is simple and durable in construction, easy and economical to construct and use, efficient in use, and otherwise adapted to meet the requirements for successful commercial use.

A still further object is to provide simple and efficient means for directing the cuttings and broken down coal away from the coal face onto the plate for delivery by the latter to the receiving conveyor.

The exact nature of the present invention, as well as other objects and features thereof, will become apparent from the following description when considered in connection with the accompanying drawings, in which:

Figure 1 is a fragmentary top plan view of an undercutting and conveying element constructed in accordance with the present invention.

Figure 2 is an enlarged fragmentary longitudinal section taken on line 2—2 of Figure 1.

Figure 3 is a view somewhat similar to Figure 2 taken on line 3—3 of Figure 1.

Figure 4 is an enlarged transverse section taken on line 4—4 of Figure 1.

Figure 5 is an enlarged section taken on line 5—5 of Figure 1, and

Figure 6 is an enlarged section taken on line 6—6 of Figure 1.

Referring in detail to the drawings, the present invention has been illustrated, by way of example, as applied to one section of a combined shaking conveyor and undercutter of the type disclosed in my copending application for U. S. Letters Patent upon Longwall mining machine, Serial No. 548,014 filed August 4, 1944. As disclosed in said copending application, the shaking conveyor and 10 undercutter includes a series of overlapping metallic plates extending along the face of the coal pillar and resting on the mine floor to form the conveyor, the edges of the plates next to the coal being fitted with replaceable steel bits to form a 15 cutting edge. Also, the conveyor and undercutter is reciprocated by a suitable driving unit in a manner similar to a common shaking conveyor, and is suitably fed toward the pillar to form an undercut therein along the floor line. The conveyor and undercutter is reciprocated with a rapid 20 movement in one direction and with a slow movement in the opposite direction to undercut and effect delivery of the coal to a receiving conveyor.

Referring to the drawings by reference characters, 1 indicates a horizontal plate forming part of a section of the conveyor and undercutter, and 2 indicates the coal pillar, along the face of which the conveyor and undercutter extends. The edge of the plate 1 next to the coal is fitted 25 with replaceable cutting bits 3 to form a cutting edge, said cutting bits being secured in socket members 3a which are fitted and secured on the edge of the plate 1 next to the coal. The back edges 3b are disposed obliquely of the plate 1 so that the socket members cause movement of cuttings and broken down coal away from the coal face onto the plate 1 during the rapid movement to the left of Figure 1.

In accordance with the present invention, the 45 major portion of the plate 1 is relatively thick and rigid, but the edge portion thereof which carries the bits 3 and which is indicated at 4 is relatively thin and free flexible vertically. Secured on the upper and lower faces of the plate 1 along the flexible edge portion 4 and the adjacent part of the thicker or rigid portion of said plate 1 are metallic strips 5 and 5a that are thin and freely flexible. These strips are preferably secured to the plate 1 by welding and at all points 50 except within the areas bounded by the dotted

lines indicated at 6 in Figure 1. It will be noted that these areas are elongated longitudinally of the plate 1 or parallel with the cutting edge of the element. Thus, similar portions of the strips 5 and 5a are left unattached to the plate 1 to provide fluidtight spaces or chambers between the strips 5 and 5a and the plate 1 into which may be introduced fluid under pressure for bulging either strip at its unattached portions away from the plate 1 and thereby causing flexing of the edge portion 4 of the latter. As shown in Figure 5, when the fluid pressure is introduced into the chambers or spaces between the upper strip 5 and the plate 1, said upper strip is bulged upwardly so as to flex the edge portion 4 of the plate 1 upwardly and thereby properly direct the cutting bits 3 to follow the floor of the mine when it slopes upwardly as at 7. On the other hand, when the fluid under pressure is introduced between the lower strip 5a and the plate 1 as shown in Figure 6, said strip 5a is bulged downwardly away from the plate 1 and causes the edge portion 4 of said plate 1 to be flexed downwardly so that the bits 3 will be caused to follow the floor of the mine when the latter slopes downwardly as indicated at 7a. When the fluid under pressure is exhausted from between both strips and the plate 1 as shown in Figure 4, the parts are normally positioned so that the bits will be disposed to enter the coal at the floor line when the floor is level.

To facilitate supply of fluid under pressure to or exhaust of the same from the chambers or points where the strips are unattached to the plate 1, the latter is provided with a transverse groove 8 in its upper face communicating with each upper chamber and a transverse groove 8a in its lower face communicating with each lower chamber, said grooves being covered by narrow extensions 9 and 9a provided on the outer edges of the strips 5 and 5a and welded to the plate 1. A relatively small bulging of the strips 5 and 5a causes considerable flexing of the portion 4 of plate 1, so that the strips 5 and 5a have ample flexibility to permit sufficient inflation and sufficient upward or downward movement of the cutting bits for all practical purposes. Obviously, a suitable supply and exhaust conduit may be suitably connected with the passages formed by the covered grooves 8 and 8a, which conduit may have a suitable control valve therein whereby to selectively cause deflation of both the upper and lower chambers, inflation of only the upper chambers, or inflation of only the lower chambers, as required. As this is elementary and forms no specific part of the present invention, it is deemed unnecessary to illustrate or detail the same herein.

As shown more clearly in Figure 1, a notch 10 is provided in the edges of plate 1 and strips 5 and 5a at the front of each bit socket 3a, and the edges of the plate and the strips are beveled rearwardly and downwardly as at 11 at the forward sides of these notches. This aids in directing the coal dust upwardly onto the plate 1 during the rapid movement of the latter rearwardly or to the left of Figure 1, the beveled edges at 11 being directly behind the oblique back edges 3b of the sockets 3a so that the elevated dust is directed inwardly onto the plate 1 and away from the coal face as before mentioned. Flexible ribs 12, preferably constructed of rubber and vulcanized or otherwise suitably attached to the upper strip 5a, extend obliquely of the element so as to provide continuations of the back edges 3b of the

sockets 3a for causing still further travel of the coal and coal dust away from the coal face on the plate 1. These ribs 12 are made of flexible material in order to provide the latter of sufficient thickness and because they are applied to those portions of the strip 5 which are free of the plate 1 and are therefore bulged upwardly in the use of the invention as illustrated in Figure 5.

In use, the pressure fluid is exhausted from between the strips 5 and 5a and the plate 1 when the floor is level as shown in Figure 4. Should the floor of the mine suddenly slope upwardly as at 7 in Figure 5, the bits 3 are properly elevated by introducing fluid under pressure between the strip 5 and plate 1 where the said strip is unattached to the latter as shown in Figure 5. This is done by simply introducing the pressure fluid through the passages formed by the covered grooves 8. However, when the floor of the mine is found to slope downwardly as at 7a in Figure 6, the pressure fluid is exhausted from between the upper strip 5 and plate 1 through the covered grooves 8, and the pressure fluid is introduced between the lower strip 5a and plate 1 through the covered grooves 8a.

From the foregoing description, it is believed that the construction and operation, as well as the advantages, of the present invention will be readily understood and appreciated by those skilled in the art. While the invention has been illustrated and described as finding embodiment in one of the plates or sections of a shaking conveyor and undercutter having rectilinear reciprocating movement, it will be apparent that the invention is capable of other applications. For instance, it may be adapted to the curved edge portion of each of the oscillating undercutting and conveying element embodying the plates indicated at 3 and 4 in my copending application for patent upon Entry driving machine, Serial No. 548,768 filed August 9, 1944, wherein the cutter bits are reciprocated in a curvilinear path. In a like manner, the invention may be adapted to the curved edge portion of the segmental element or section indicated at 1a in my copending application for patent upon Longwall mining machine, Serial No. 589,483 filed April 21, 1945.

Minor changes may be made in details of construction illustrated and described, such as fall within the scope of the invention as claimed.

What I claim is:

1. An undercutting and conveying element, for coal mining machines, adapted to be reciprocated on the mine floor with a rapid rearward stroke and a slow cutting and conveying stroke, comprising a substantially horizontal plate having an edge portion which is freely flexible vertically, cutting bits mounted on the free edge of said flexible edge portion, and means to selectively flex said flexible portion downwardly or upwardly, at will.
2. An undercutting and conveying element, for coal mining machines, adapted to be reciprocated on the mine floor with a rapid rearward stroke and a slow cutting and conveying stroke, comprising a substantially horizontal plate having an edge portion which is freely flexible vertically, cutting bits mounted on the free edge of said flexible edge portion, and fluid pressure operated means to selectively flex said flexible edge portion downwardly or upwardly, at will.
3. An undercutting and conveying element, for coal mining machines, adapted to be reciprocated on the mine floor with a rapid rearward stroke and a slow cutting and conveying stroke, com-

prising a substantially horizontal plate having an edge portion which is freely flexible vertically, cutting bits mounted on the free edge of said flexible edge portion, freely flexible strips secured on the upper and lower surfaces of said flexible edge portion and an adjacent portion of said plate so as to leave confined areas of the strips unattached to the plate inwardly of said flexible edge portion, and means to facilitate supply of pressure fluid to or exhaust of the same from between the unattached portions of the strips and the plate, whereby to selectively bulge the strips and cause upward or downward flexing of the flexible edge portion of the plate, at will.

4. An undercutting and conveying element, for coal mining machines, adapted to be reciprocated on the mine floor with a rapid rearward stroke and a slow cutting and conveying stroke, comprising a substantially horizontal plate having an edge portion which is freely flexible vertically, cutting bits mounted on the free edge of said flexible edge portion, freely flexible strips secured on the upper and lower surfaces of said flexible edge portion and an adjacent portion of said plate so as to leave confined areas of the strips unattached to the plate inwardly of said flexible edge portion, and means to facilitate supply of pressure fluid to or exhaust of the same from between the unattached portions of the strips and the plate, whereby to selectively bulge the strips and cause upward or downward flexing of the flexible edge portion of the plate, at will, said last named means comprising grooves in the surfaces of the plate and extensions on the strips covering said grooves to form supply and exhaust passageways for the pressure fluid.

5. An undercutting and conveying element, for coal mining machines, adapted to be reciprocated on the mine floor with a rapid rearward stroke and a slow cutting and conveying stroke, comprising a substantially horizontal plate having an edge portion which is freely flexible vertically, cutting bits mounted on the free edge of said flexible edge portion, freely flexible strips secured on the flexible edge portion and an adjacent portion of the plate to the upper and lower surfaces thereof, said strips having areas unattached to the plate at enclosed points so that the unattached portions of the plates form diaphragms adapted to be flexed away from the plate to selectively flex the flexible edge portion of the plate upwardly or downwardly at will, and means to facilitate selective supply of pressure fluid to or from between the unattached portions of the strips and the plate.

6. An undercutting and conveying element, for coal mining machines, adapted to be reciprocated on the mine floor with a rapid rearward stroke and a slow cutting and conveying stroke, comprising a substantially horizontal plate having an edge portion which is freely flexible vertically, cutting bits mounted on the free edge of said flexible edge portion, freely flexible strips secured on the flexible edge portion and an adjacent portion of the plate to the upper and lower surfaces thereof, said strips having areas unattached to the plate at enclosed points so that the unattached portions of the plates form diaphragms adapted to be flexed away from the plate to selectively flex the flexible edge portion of the plate upwardly or downwardly at will, and means to facilitate selective supply of pressure fluid to or from between the unattached portions of the strips and the plate, and flexible ribs secured on the upper strip obliquely of the plate to cause movement of coal away from the working face from the bits on the rapid rearward stroke of the element, said ribs being attached to the areas of the upper strip which are unattached to the plate.

7. An undercutting and conveying element, for coal mining machines, adapted to be reciprocated on the mine floor with a rapid rearward stroke and a slow cutting and conveying stroke, comprising a substantially horizontal plate, cutting bits mounted on a free edge of said plate, said plate having notches in said free edge thereof, one in front of each cutting bit, the edge of the plate at the forward side of each notch being beveled rearwardly and downwardly whereby to cause coal dust to be delivered upwardly onto the plate upon its rapid rearward stroke.

8. An undercutting and conveying element, for coal mining machines, adapted to be reciprocated on the mine floor with a rapid rearward stroke and a slow cutting and conveying stroke, comprising a substantially horizontal plate, cutting bits mounted on a free edge of said plate, said plate having notches in said free edge thereof, one in front of each cutting bit, the edge of the plate at the forward side of each notch being beveled rearwardly and downwardly whereby to cause coal dust to be delivered upwardly onto the plate upon its rapid rearward stroke, and sockets for said bits secured on the plate in front of each notch, said sockets having oblique rear edges to cause travel of the coal dust away from the working face as it is delivered onto the plate by traveling up the beveled edges.

CHARLES E. TIBBALS.
